UNITED STATES PATENT OFFICE.

JOHN W. AULSON, OF LYNN, MASSACHUSETTS, ASSIGNOR TO MERROW MACHINE CO., OF SALEM, MASSACHUSETTS, A CORPORATION OF MASSACHUSETTS.

BLACKING-MACHINE.

1,270,684.

Specification of Letters Patent. Patented June 25, 1918.

Application filed April 14, 1917. Serial No. 162,819.

To all whom it may concern:

Be it known that I, JOHN W. AULSON, a citizen of the United States of America, and a resident of Lynn, in the county of Essex 5 and Commonwealth of Massachusetts, have invented certain new and useful Improvements in Blacking-Machines, of which the following is a specification.

This invention relates to machines for applying blacking or coloring matter to the face of a hide in order to give it a required finish, and it has for its object the provision 10 of means whereby better work may be accomplished and the adjustments of the feed roll and the various operating brushes may be quickly made to bring these devices into proper position relatively to each other.

The invention consists in certain novel features of construction and arrangement of 20 parts which will be fully understood by reference to the description of the drawings and to the claims hereinafter given.

For the purpose of illustrating the invention one preferred form thereof is illustrated 25 in the drawings, this form having been found to give satisfactory and reliable results, although it is to be understood that the various instrumentalities of which the invention consists can be variously arranged 30 and organized, and that the invention is not limited to the precise arrangement and organization of these instrumentalities as herein shown and described.

Of the drawings:

35 Figure 1 represents an end elevation of a machine embodying the principles of the present invention.

Fig. 2 represents a vertical section of the same.

40 Fig. 3 represents an elevation of the saddle and adjustable support carrying the bearings for the feed roll shaft and the shafts of the various brushes.

Fig. 4 represents a plan of the saddle.

45 Fig. 5 represents a plan of the adjustable bearing supporting member, and

Fig. 6 represents a section on line 6—6 on Fig. 3.

50 Similar characters designate like parts throughout the several figures of the drawings.

In the drawings, 10 is the frame of a machine having revolvably mounted in bearings thereon a shaft 11 having a bed roll 12

mounted thereon and revoluble therewith. 55 An inclined table 13 is provided over which the hide is fed between the pan 14 and said bed roll 12 until it is engaged by the revolvble blacking brush 15 which retains the hide on said bed roll and causes it to be fed in 60 contact with the bed roll 12 beneath the distributing brush 16 and finishing brush 17. The pan 14 is partially filled with the liquid material to be used upon the hides. This material may be blacking or any desired col- 65 oring matter.

Partly submerged in the pan 14 is a feed roll 18 which deposits a portion of the liquid material upon the brush 15 from which said material is deposited upon the surface of the 70 hide on the bed roll 12. The material thus disposed upon the hide is distributed over the entire surface of the hide by the distributing brush 16, and as said hide passes beneath the brush 17 the surface of the hide 75 is finished, the material being more evenly spread over the surface and polished by the latter brush.

The bed roll 12 revolves in the direction of the arrow *a* on Fig. 2 of the drawings and 80 all surplus liquid which may be disposed thereon is removed therefrom by means of the scraper 19, which may be of any well-known construction. The frame 10 has revolvably mounted therein a driving shaft 20 85 to which rotary movement is imparted by a pulley 21 and belt 22. On the shaft 20 is a pinion 23 meshing with an intermediate pinion 24 which in turn meshes with the teeth of a gear 25 secured to the shaft 11, 90 and to which rotary movement is imparted by the train of gears 23, 24, and 25.

Loosely mounted on the shaft 11 is an arm 26 having an operating handle 27 by which 95 said arm may be moved about the axis of the shaft 11 and clamped in adjusted position by means of the clamping member 28 coacting with the slotted arc 29 secured to the frame 10 at 30.

The shaft 31 of the feed roll 18 has secured 100 thereto the gear 32 meshing with the pinion 33 on a stud 34 carried by the arm 26, said pinion 34 having secured thereto a gear 35 driven by the gear 25 on the shaft 11.

Secured to each end of the frame 10 is a 105 saddle 36, to one end of which is adjustably secured the bearing 37 for the shaft 31 of the feed roll 18. The rear end of the saddle

36 has adjustably mounted thereon the bearing 38 for the shaft 39 of the finishing brush 17.

By means of this construction the bed roll 18 and finishing brush 17 may be adjusted horizontally toward and from the bed roll 12 and the bearings 37-39 for the shafts 31, 39 then clamped in adjusted position by means of the nuts 40-41 respectively.

10 The saddle 36 has projecting upwardly therefrom an arm 42 which is slightly inclined toward the rear and is provided with a slot 43 extending longitudinally thereof. Movable lengthwise of the arm 42 is a cross member 44 having a transverse slot 45 in which the arm 42 is positioned with its edges in contact with the side walls of said slot 45 as shown in Fig. 6.

A bolt 46 extends through the slot 43 of 20 the arm 42 and also through the cross member 44, the outer threaded end of which is provided with a clamping nut 47 by which the member 44 is prevented from being displaced relatively to the arm 42.

25 The member 44 is provided with an ear 48 having a threaded opening 49 therethrough in which is mounted the threaded shank 50 of the adjusting member 51 having a head 52 provided with holes to receive a spanner wrench when it is desired to adjust the 30 height of the member 44 relatively to said arm 42.

The lower end of the member 51 has a reduced end 53 freely revoluble in an ear 54 35 on the saddle 36 and prevented from end movement by the nut 55. The member 44 is provided with a rearward projection 56 having a hole therein in which is positioned the threaded shank 57 of a bearing 58 for 40 the shaft 59 of the distributing brush 16.

The bearing 58 may be raised and lowered in the hole in said projection 56 and then locked in adjusted position by the nuts 60 on said threaded shank 57. The member 44 is 45 also provided with a forward projection 61 having a radial slot 62 through which extends the threaded shank 63 of a bearing 64 for the shaft 65 of the brush 15, said shank being provided with a clamping nut 630.

50 The bearing 64 is provided with a rib 66 which is positioned between the side rails 67 on the upper face of said forward projection 61. It is obvious that by means of this construction the brushes 15 and 16 may 55 be adjusted vertically simultaneously while the brush 16 may be independently adjusted vertically for fine adjustment and the brush 15 may be adjusted horizontally toward and from the brush 16. In like manner, means is 60 herein provided whereby the feed roll 18 may be adjusted horizontally toward and from the brush 15 with which it coacts.

65 The finishing brush is adapted to be moved horizontally so that it will assume the proper position relatively to the bed roll 12

and then the other adjustments may be quickly made to bring the brushes 15 and 16 and the feed roll 18 into proper position relatively to each other and also to the bed roll 12.

70 It is believed that the operation and many advantages of the invention will be fully understood from the foregoing description.

Having thus described my invention, I 75 claim:

1. In a device of the class described, the combination of a revoluble bed roll; a pan to contain liquid; a feed roll revoluble therein; a revoluble liquid receiving brush contacting therewith; a revoluble finishing brush at the rear of said bed roll and contacting therewith; an intermediate brush revolubly mounted between the other brushes in contact with said bed roll; means for simultaneously adjusting the liquid receiving and intermediate brushes vertically; and means whereby said liquid receiving brush may be moved toward and from said intermediate brush.

2. In a device of the class described, the 90 combination of a frame; a revoluble bed roll thereon; a fixed member secured to the upper part of each end of said frame and provided with an upwardly extending arm; a slidable member on said arm; means for 95 adjusting said slidable member; a pan to contain liquid; a feed roll therein; a revoluble liquid receiving brush on said slidable members; a revoluble finishing brush on said fixed members; and a revoluble intermediate 100 brush also mounted on said slidable members between the outer brushes.

3. In a device of the class described, the combination of a frame; a revoluble bed roll thereon; a fixed member secured to the 105 upper part of each end of said frame and provided with an upwardly extending arm; a slidable member on said arm; means for adjusting said slidable member; a pan to contain liquid; a feed roll therein; a revoluble liquid receiving brush on said slidable members; a revoluble finishing brush on said fixed members; a revoluble intermediate 110 brush also mounted on said slidable members between the outer brushes; and means for adjusting said intermediate brush relatively to said slidable members and parallel to said arms.

4. In a device of the class described, the combination of a frame; a revoluble bed roll 120 thereon; a fixed member secured to the upper part of each end of said frame and provided with an upwardly extending arm; a slidable member on said arm; means for adjusting said slidable member; a pan to 125 contain liquid; a feed roll therein; a revoluble liquid receiving brush on said slidable members; a revoluble finishing brush on said fixed members; a revoluble intermediate brush mounted on said slidable members be- 130

tween the outer brushes; a support for each end of the intermediate brush shaft provided with a threaded shank extending through an ear on said slidable member; and 5 clamping nuts on said threaded shank on opposite sides of said ear.

5. In a device of the class described, the combination of a frame; a revolute bed roll thereon; a fixed member secured to the upper 10 part of each end of said frame and provided with an upwardly extending arm and a laterally extending ear; a slidable member on said arm provided with a laterally projecting threaded ear; a screw extending through 15 said threaded ear revolutely mounted in the ear on said frame and prevented from end movement; two revolute coacting brushes on said slidable members on opposite sides of said upwardly extending arms; a pan 20 to contain liquid; a feed roll therein adapted to deposit the liquid from said pan onto one of said brushes.

6. In a device of the class described, the combination of a frame; a revolute bed roll thereon; a fixed member secured to the upper 25 part of each end of said frame and provided with an upwardly extending arm and a laterally extending ear; a slidable member on said arm provided with a laterally projecting threaded ear; a screw extending 30 through said threaded ear revolutely mounted in the ear on said frame and prevented from end movement; two revolute coacting brushes on said slidable members on opposite sides of said upwardly extending arms; a pan 35 to contain liquid; a feed roll therein adapted to deposit the liquid from said pan onto one of said brushes; and a revolute finishing brush adjustably mounted on said 40 fixed members.

7. In a device of the class described, the combination of a frame; a revolute bed roll thereon; a fixed member secured to the upper part of each end of said frame and 45 provided with an upwardly extending slotted arm and a laterally extending ear; a slidable member on said arm provided with a laterally projecting threaded ear; a headed member on said slidable member extending 50 through the slot of said arm; a screw ex-

tending through said threaded ear revolutely mounted in the ear on said frame and prevented from end movement; two revolute coacting brushes on said slidable members on opposite sides of said upwardly extending arms; a pan to contain liquid; and a feed roll therein adapted to deposit the liquid from said pan onto one of said brushes. 55

8. In a device of the class described, the combination of a frame; a revolute bed roll thereon; a fixed member secured to each end of said frame and provided with an upwardly extending arm, said member having a slot in the rear end thereof; a slidable 60 member on said arm; revolute brushes supported on said slidable members on opposite sides of said upwardly extending arms; a bearing at the rear end of each fixed member provided with a threaded shank extending 65 through said slot; a clamping nut on said threaded shank; a revolute finishing brush supported in said bearings; a pan to contain liquid; and a feed roll therein adapted to deposit liquid on the revolute 70 brush coacting therewith.

9. In a device of the class described, the combination of a frame; a revolute bed roll thereon; a member secured to each end of said frame and provided with an upwardly 80 extending arm; a slidable member on said arm having a forwardly extending slotted ear and a rearwardly extending ear with a cylindrical hole therein parallel to said arm; a bearing provided with a threaded shank 85 extending through said slot; a clamping nut for said shank; a bearing having a threaded shank extending through said hole; nuts on said shank on opposite sides of said ear; means for adjusting said slidable member on 90 said arm; revolute brushes supported by said bearings; a pan to contain liquid; and a feed roll therein adapted to deposit liquid on the revolute brush coacting therewith. 95

Signed by me at 4 Post Office Square, Boston, Mass., this 29th day of March, 1917.
JOHN W. AULSON.
